UNITED STATES PATENT OFFICE.

BERNARD D. WILLIS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed February 24, 1926. Serial No. 90,241.

This invention relates to telephone systems in general, but more specifically to toll or long distance trunking systems in which the toll connections within a certain area are 5 established and supervised from a main toll board.

In larger telephone systems comprising several exchanges, or extending over an area including several surrounding communities, 10 the practice of completing and supervising all toll connections within that area from a main toll board centrally located with respect to the other exchanges or communities is sometimes found desirable. All the 15 toll lines incoming from distant points into a telephone system following this practice terminate at the main toll board from where toll service lines extend to the various exchanges in the local system. For well 20 known engineering reasons, the trunk lines between exchanges, especially within the limits of a city, are usually run in cables, while the trunk lines between cities are usually open-wire lines. It is therefore common 25 practice to terminate the incoming open-wire lines at some outlying exchange from where they are extended by cable to the main toll board.

Should a toll connection be desired with 30 a subscriber served by the outlying exchange through which the incoming toll trunks pass, the toll connection would ordinarily extend from the distant point over a toll trunk through this outlying exchange to the 35 main toll board at which the connection would be completed by the toll operator over a local service toll line back again to the outlying exchange to the local subscriber. Inasmuch as the transmission losses in toll 40 connections is an important consideration, especially when the trunk lines are run in cables, the transmission losses in cables being comparatively high, it becomes desirable 45 to reduce the length of the talking circuit of a toll connection as much as possible and especially desirable to eliminate the looping back of a connection, as would ordinarily be necessary to complete a connection such as described above. By this invention, means have been provided whereby 50 such a toll connection may be completed and supervised from the main toll board at the same time making it possible to establish a talking connection over the most direct 55 route to the called subscriber, eliminating

the sections of trunk lines from the outlying exchange to the toll board and back again from the talking circuit.

A section of a telephone system employing the scheme proposed by this invention is 60 diagrammatically shown in the accompanying drawing comprising Fig. 1 and Fig. 2. In Fig. 1, the various switches and circuits pertaining to the invention are represented diagrammatically and are shown more in 65 detail by means of the usual schematic circuit diagrams in Fig. 2. The corresponding elements are lettered and numbered the same in both figures.

Referring to Fig. 1 of the drawings, the 70 trunk line comprising conductors 101 and 102 is one of the incoming toll lines from some distant city. The toll lines terminate at the exchange Y from where they extend to the main toll board located in exchange 75 X, terminating in jacks, such as J. The conductors 103 and 104 comprise that section of an incoming trunk line extending from the exchange Y to the toll board. The exchange Y in this instance, is an automatic exchange. The conductors 305 and 306 comprise one of the toll service lines extending from the main toll board to the exchange Y, accessible at the toll board in jacks such as jack J'. Each toll service 80 line terminates at the automatic exchange Y in a toll transmission selector. The toll transmission selectors have access to toll connectors which in turn have access to the subscriber's line served by the automatic 85 exchange Y.

At the automatic exchange Y special connecting links, such as C—C', to which this invention particularly pertains, have access on one end to the incoming toll trunks passing through this exchange from the distant point to the toll board, and on the other end to the toll service lines extending from the toll board to the automatic exchange Y. A special line comprising conductors 201 and 202 extends from the main toll board to the automatic exchange Y, terminating there in the line switch LS. At the main toll board, the dial S' may be bridged across this line by means of a key. The line switch LS has 95 access in its banks to all the connecting links, such as C—C'. The toll operator at the main toll board is provided with cords, such as cord O.

A brief description of the above mentioned 110

apparatus will now be given, particular reference being made to Fig. 2.

The connecting link C—C' consists essentially of two separate vertical and rotary switching mechanisms of the well known Strowger step-by-step type whose wipers may be inductively connected together. The control circuits for these switching mechanisms are interconnected and are so arranged that a common line relay first controls the operation of the switching mechanism C, which has access to the toll service lines, and then controls the operation of the switching mechanism C', which has access to the incoming toll trunks.

The line switch LS is an ordinary rotary line switch having wipers which rotate in one direction only and which have no normal position.

The cord O is provided with the dial S, the telephone set TS, and the supervisory lamps L and L'. The generator G is common to all the cords at the operator's position.

A toll transmission selector and a connector are not shown, since they do not pertain particularly to the invention, and are merely represented by rectangles labelled EF and H, respectively. Reference may be made, however, to the Wicks Patent No. 1,633,149, granted June 21, 1927, in which is shown a suitable toll transmission selector and toll connector.

A clear understanding of the invention and its objects, and also other features not specially mentioned, may be obtained from a detailed description of the operation of the various switches and circuits pertaining to the invention. For this purpose, it will be assumed that a long distance connection is desired by a party in some distant city with the subscriber at the substation A, whose line terminates in the automatic exchange Y. To establish this connection, the toll operator in the distant city selects a toll trunk extending to the exchange Y and applies ringing current thereto. It may be assumed that the trunk line comprising conductors 101 and 102 is the trunk selected. The ringing current incoming over conductors 101 and 102, which extend by way of armatures 86 and 87 and their resting contacts, conductors 103 and 104, closed springs 7 and 8, to the drop signal 2, operates this signal which notifies the toll operator at the main toll board of the incoming toll call. In response to this signal, the toll operator inserts the plug of an idle cord, such as plug P of the cord O, into the jack J and operates the listening key K'. The distant toll operator then informs the local toll operator at the main toll board of the connection desired. Since it has been assumed that the toll call is for the subscriber at substation A in the exchange Y, the toll operator inserts the plug P' into the

jack of an idle toll service line extending back to the automatic exchange Y. It may be assumed that the trunk selected is the one comprising conductors 305 and 306, terminating in the jack J'. After inserting the plug P' into the jack J', the operator throws the key K² to the dialling position, thereby bridging the dial S directly across the conductors 305 and 306 by the closure of contacts 15 and 16 and the opening of contacts 15' and 16'. The operator then dials the directory number of the subscriber at substation A. In response to the bridging of the dial across the line conductors and the dialling of the digits by the operator, the toll transmission selector EF and the toll connector H function to establish a connection to the desired substation in the well known manner. The detailed operation of the toll transmission selector and the toll connector are described in the above mentioned Wicks patent, to which reference may be made.

It may be assumed that the line to substation A is idle at the time the connector is operated which will be indicated by the lighting of the lamp L' after the operator has completed the dialling, as is described in the above mentioned application. After finishing dialling and perceiving the illumination of the lamp L', the operator at the main toll board may signal the subscriber at substation A at will by operating the key K² to the ringing position. Ringing current applied to the conductors 305 and 306 starts the usual signalling operation which causes the ringing of the bells at the subscriber's substation A.

While the called subscriber is being rung, the operator may proceed to prepare a connecting link at the automatic exchange, such as connecting link C—C' for establishing a talking connection from the toll trunk to conductors 305' and 306' at the automatic exchange directly, the purpose being to eliminate the loop extending from the automatic exchange to the toll board and then back again to the automatic exchange from the talking circuit. Each toll trunk passing through the automatic exchange and terminating at the toll board, and also each toll service line extending from the toll board back to the automatic exchange is assigned a certain number. The toll service lines are accessible in the banks of the switching mechanisms, such as C, and the incoming toll trunks are accessible in the banks of the switching mechanisms, such as C', a particular line or trunk being accessible in the set of bank contacts corresponding to the number of that line or trunk. To accomplish the purpose described above, the operator operates the dial key K³ and then dials the numbers 56 and 34, consecutively, it being assumed that these are the numbers of

the toll service lines and the incoming trunk lines used, respectively. Operating the dial key K^3 bridges the dial S' across the conductors 201 and 202, thereby closing a circuit 5 for the line relay 21 of the line switch LS. Relay 21 operates and places ground on the upper terminal of switching relay 22 and also connects the test wiper 32 to the junction of the lower winding of the switching 10 relay 22 and the stepping magnet 23 at armature 24. If the conductors terminating at the contacts upon which the switch wipers 31-33, inclusive, are positioned at this time extend to a busy connecting link, ground 15 will be present on the bank contact engaged by the wiper 32. This will cause the operation of the stepping magnet 23 in the well known manner over a circuit which may be traced from ground on the bank contact 20 engaged by wiper 32, armature 27 and the resting contact, working contact and armature 24, interrupter springs 29, through the winding of the stepping magnet 23 to battery. Stepping magnet 23 operates, 25 opens the interrupter springs 29, thereby opening its own circuit, and in deenergizing, steps the wipers 31-33, inclusive, into engagement with the next set of bank contacts. If the conductors terminating in this next 30 set of bank contacts also extend to a busy connecting link, the stepping magnet 23 will again function to step the wipers into engagement with the next set of bank contacts. This operation will be repeated until the 35 wipers 31-33, inclusive, are rotated into engagement with the set of bank contacts terminating conductors connected to an idle connecting link, an idle connecting link being represented by the absence of ground on 40 the test contact engaged by the wiper 32. Then, due to the absence of ground on the test contact, no circuit is again closed for the stepping magnet 23, and the short circuit is also removed from the switching relay 22. The switch wipers are arrested in 45 this position and switching relay 22 is energized over a circuit from ground at the working contact and armature 25, through the winding of the switching relay 22, closed 50 interrupter contacts 29, through the winding of the stepping relay 23 to battery. The resistance of the winding of relay 22 does not permit sufficient current to flow to cause the operation of stepping magnet 23 at this 55 time. Relay 22 operates, however, and disconnects conductors 201 and 202 from their normal battery and ground connections, and connects them to the switch wipers 31 and 33 at armatures 26 and 28 and their working 60 contacts, respectively; and also places ground potential on the bank contact engaged by wiper 32 at armature 27 and the working contact. In the description of the 65 operation of the line switch LS, it has been assumed that the wipers 31-33, inclusive, may not be positioned on contacts connected to an idle connecting link at the time the key K^3 is operated. It will become obvious from later description, however, that the wipers of the line switch LS by reason of 70 other considerations to be explained later will most probably be standing opposite an idle trunk, providing there is one idle when the key K^3 is thrown.

It may be assumed that the wipers 31-33, 75 inclusive, are in, or were rotated into, engagement with the bank contacts 34-36, inclusive, terminating the connecting link C-C', which may be assumed to be idle at this time. The connecting of the conductors 201 and 202 to the wipers 31 and 33, respectively, closes a circuit for the line relay 43. Line relay 43 operates and closes a circuit for the release relay 44 at armature 54 and the working contact. Release relay 44 80 operates and prepares the impulse circuit for the vertical magnet 48 at armature 56, and also places ground on the holding conductor 37 at armature 55, this occurring before the slow acting line relay 21 in the line 85 switch LS has had time to restore its armature following the opening of its circuit which occurs when switching relay 22 energizes. The switching relay 22 is now held operated from ground supplied to the release conductor 37.

The foregoing operations of the line switch LS and the operations of relays 43 and 44 all take place responsive to the operation of the key K^3 . In response to the 90 dialling of the digit 5, the line relay 43 deenergizes and energizes again a corresponding number of times. The first time the armature 54 falls back, a ground impulse is sent to the vertical magnet 48 by way of 95 armature 53 and its resting contact, armature 51' and its resting contact, armature 54 and its resting contact, armature 56 and its working contact, closed springs 64, through the winding of the series relay 45, through 100 the winding of the vertical magnet 48 to battery. Vertical magnet 48 operates and elevates the switch wipers 81-84, inclusive, one step. This operation shifts the vertical off normal springs, opening springs 64 and 105 closing springs 63. Series relay 45 also energizes and operates its armature 57. The remaining impulses of the first digit traverse the same path as the initial impulse, except that the path now includes springs 63 110 and armature 57 and its working contact, and excludes springs 64, series relay 45 being slow acting, maintaining its armature attracted throughout the vertical movement. Wipers 81-84, inclusive, are thus raised 115 opposite the fifth level of bank contacts. At the termination of the first series of impulses, relay 45 falls back and prepares a circuit for the rotary magnet 49 at armature 120 57 and its resting contact.

4

In response to the dialling of the second digit 6, line relay 43 again deenergizes and energizes a corresponding number of times, at each deenergization closing a circuit which may be traced from ground by way of armature 53 and its resting contact, armature 51' and its resting contact, armature 54 and its resting contact, armature 56 and its working contact, springs 63, armature 57 and its resting contact, conductor 61², normally closed springs controlled by armature 61, armature 59 and its resting contact, through the winding of the rotary series relay 47, through the winding of the rotary magnet 49 to battery. Rotary series relay 47 operates and at armature 61 changes the circuit for the rotary magnet 49 to include the working contact and armature 61 and exclude armature 59 and its resting contact. Relay 47 also closes a circuit for the lower winding of the two-step relay 46 at armature 60 and the working contact. The two-step relay 46 partially energizes and operates its armature 58, thereby preparing a circuit for fully operating, which it is prevented from doing at this time since ground is connected to both ends of its upper winding. From the foregoing description, it might appear that the conductor 61² could be connected directly to the armature 59, thus dispensing with armature 61 and the contacts controlled thereby, since armature 59 does not operate until the completion of the rotary movement. Armature 61 and the contacts controlled thereby are provided, nevertheless, to assure the proper operation of the rotary magnet 49 even though the two-step relay 46 is not properly adjusted and permits the separation of armature 59 and its resting contact when only partially energized. To continue, the rotary magnet 49 operates and rotates the switch wipers 81-84, inclusive, into engagement with the sixth set of contacts in the fifth level, this set comprising the contacts 91-94, inclusive, at which the toll service line comprising conductors 305 and 306 is accessible. At the end of the rotary movement, rotary series relay 47 deenergizes and removes the short circuit from the upper winding of the two-step relay 46. Two-step relay 46 is now energized over its two windings in series from ground by way of armature 55 and the working contact, armature 58 and the working contact, through the upper and lower windings of the two-step relay 46 to battery. The resulting increased magnetic pull causes the operation of armature 59, thereby preparing a circuit for the vertical magnet 48' of the switching mechanism.

The operator now dials the digit 3, and, in response to the impulses produced thereby, ground impulses are again sent over a circuit which is the same as that previously traced to armature 59 from where it extends

by way of the working contact of armature 59, normally closed off normal springs 46', through the winding of the vertical series relay 45' through the winding of the vertical magnet 48' to battery. Vertical magnet 48' operates, just as did vertical magnet 48, and raises the wipers 81'-83', inclusive, opposite the third level of bank contacts, shifting the off normal springs 63' and 64', on the first step of the wipers, thereby changing the impulsive path for the remaining impulses to include the springs 63' and armature 57' and the working contact and to exclude springs 64', so that when relay 45' falls back the operating circuit will be shifted to rotary magnet 49'.

The toll operator will not dial the last digit immediately, since the dialling of the last digit, as will become evident from later descriptions, initiates the operation of connecting the toll trunk conductors 101 and 102 directly to the conductors 306' and 305', at the same time disconnecting the section of the toll line comprising conductors 103 and 104. It is desirable that the toll operator have supervision directly through her position until the calling and called parties are actually in talking communication. She will, therefore, wait until this has been verified before dialling the last digit. In the meantime, she may disconnect her telephone set from the cord O and answer other calls.

Should the distant toll operator wish to signal the toll operator at any time before the connection has finally been completed, she can do so by again applying ringing current to the toll conductors 101-102 still connected to the toll conductors 103 and 104. The supervisory relay 3, bridged across the talking conductors of the cord, will then operate and will close a locking circuit for itself and for the supervisory lamp L at armature 5. This relay will remain operated and the lamp will remain lighted until the main toll operator again connects her telephone set across the toll line in question by actuating the listening key K' to converse with the distant toll operator. Operating the key K' bridges the telephone set across the talking conductors of the cord and causes the separation of the springs 6 opens the locking circuit for the supervisory relay 3 and also opens the circuit for the lamp L.

When the subscriber at the substation A removes his receiver, the lamp L' is extinguished, thereby notifying the toll operator that the called subscriber has answered. She may now signal the distant toll operator by actuating the key K to the signalling position, thereby connecting the generator G to the toll trunk conductors 103 and 104 at springs 17' and 17, respectively, and also connect her telephone set to the cord O by actuating key K'. When the distant toll

operator responds, the toll operator at the main toll board may inform her that the desired party is on the line, whereupon the distant toll operator will complete the talking connection between the two subscribers.

After the two subscribers have been placed in talking communication, the main toll operator will dial the last digit, which in this instance is the digit 4. In response thereto, ground impulses produced by the deenergizations of the line relay 43 traverse the path previously traced to armature 57' from where it extends by way of the resting contact of this armature, normally closed springs controlled by armature 61', resting contact and armature 59', through the winding of the rotary series relay 47' through the winding of the rotary magnet 49' to battery. Relay 47' operates and excludes armature 59' from the above traced circuit by the actuation of armature 61'. A circuit is also closed for the switching-control relay 46' at armature 60'. Relay 46' operates and prepares a circuit for the switching relay 71 at armature 58' and opens a point in the original circuit of the rotary magnet 49' at armature 59'. Switching relay 71' is not operated, however, until the ground connection is removed from the lower terminal of its winding which will take place when relay 47' deenergizes and releases its armatures at the end of the rotary movement. In response to the impulses sent to the rotary magnet 49', this magnet operates to rotate the wipers into engagement with the fourth set of bank contacts in the third level, comprising the bank contacts 91'-93', inclusive, at which the toll trunk comprising conductors 101 and 102 is accessible.

At the termination of the impulses of the last digit, relay 47' deenergizes and removes the ground from the lower terminal of the winding of the switching relay 71 by releasing armature 60'. Switching relay 71 is operated and relay 46' is maintained operated over a circuit which may be traced from the grounded conductor 37, armature 58' and its working contact, through the winding of the switching relay 71, through the winding of the switching control relay 46' to battery. Relay 71 operates and connects the wipers 82 and 83 to the wipers 82' and 83', at armatures 75 and 76, respectively; closes a circuit for the switching relay 85, which is individual to the trunk comprising conductors 101 and 102, at armature 74; closes a circuit for the shunt-removing relay 12 which is individual to the toll service line comprising conductors 305 and 306 at armature 73; and at armature 72 closes a circuit for the holding relay 42, which may be traced from ground supplied to the release trunk conductor 98 from the toll transmission selector, bank contact 94, wiper 84, working contact and armature

72, through the winding of the holding relay 42 to battery. Relay 85 operates and disconnects the section of the trunk line comprising conductors 103 and 104 and connects the toll line 101-102 to the toll service line 305'-306' by way of armatures 86 and 87 and the working contacts, bank contacts 92' and 93', wipers 82' and 83', armatures 75 and 76 and their working contacts, condensers 77 and 78, wipers 82 and 83, bank contacts 92 and 93, and conductors 99 and 97. Relay 12 operates and places the two windings of the impedance coil 11 in series with the line conductors 305 and 306 at armatures 14 and 13, respectively. The purpose of the impedances in the trunk conductors 305 and 306 which extend to the main toll board is to prevent the talking current from being shunted through the supervisory relay 4 in the main toll operator's cord. Even though the main talking connection now extends over the direct route through the connecting link C-C', the main toll operator still has supervision of the connection over the trunk line comprising conductors 305 and 306 and the cord O. Relay 42 operates when its circuit is closed by relay 71 and places a holding ground on the conductor 37 at armature 52, at the same time removing ground from the bank contact 35, the latter operation permitting the line switch LS to release, i. e., restore its relay 22. At armature 53, relay 42 closes a circuit for the guarding relay 41, which energizes and again connects ground to bank contact 35. Relay 42 also opens the circuit for the release relay 44. Relay 44 releases and removes ground supplied to conductor 37 at armature 55, ground being maintained thereon, however, by armature 52 and its working contact; and prepares a point in the circuits of the release magnets 50 and 50' at armature 56 and the resting contact. The switching mechanisms C and C' are now held operated by ground over conductor 98 from the toll transmission selector, which keeps relay 42 energized. At the line switch LS, the restoration of the switching relay 22 again connects ground to the conductor 202 and connects the line relay 21 to the conductor 201. In all probability, the toll operator will not have restored the key K³ at the time that the line relay 21 is again connected to the conductor 201, and, accordingly, before the slow acting line relay 21 has had time to operate, the line relay 21 again operates, as previously described, and (since contact 35 is now grounded) causes the line switch LS to rotate the wipers 31-33 into engagement with the next set of contacts connected to an idle connecting link similar to connecting link C-C'. The line relay and the release relay of that connecting link similar to relays 43 and 44, will then be

operated to prepare this link for operation. When the toll operator restores the key K^3 , however, the bridge across the conductors 201 and 202, is opened, thus opening the 5 circuit of this second operated line relay. This relay will deenergize and open the circuit of the second operated release relay. It may be mentioned, however, that it is not necessary for the main toll operator to 10 restore the key K^3 , should she make successive connections of the type just described, since the line switch LS automatically operates to position its wipers on a set of contacts connected to an idle connecting link 15 immediately following the completion of the dialling of the four digits for setting up a connection.

When the subscriber at the substation A replaces his receiver at the end of the 20 conversation, lamp L' is again lighted. In response to the lighting of the lamp L' , indicating the termination of the conversation, the toll operator removes the plug P' from the jack J' . The removal of the plug P' 25 from the jack J' causes the release of the toll connector and the toll transmission selector in the well known manner. Ground potential is then removed from the release conductor 98, thereby opening the circuit for the holding relay 42. Relay 42 deenergizes and removes the ground supplied to the holding conductor 37 at the working contact of armature 52. Ground is maintained on conductor 37, however, until armature 51 is 30 released by way of this armature and its working contact, and resting contact and armature 52. At armature 53, the circuit of relay 41 is opened as soon as relay 42 deenergizes, and a point in the release circuit 35 is closed. Relay 41 releases a short time after its circuit is opened and removes ground from conductor 37 at armature 51, thereby opening the circuit of relay 46 the switching relay 71 and the switching-control 40 relay 46'. In releasing, relay 41 also closes the circuit for the release magnets 50 and 51, which may be traced from ground at armature 53 and its resting contact, armature 51' and its resting contact, armature 54 and its 45 resting contact, armature 56 and its resting contact, through the off normal springs 62, closed upon the first vertical step of the wipers of the switching mechanism C through the winding of the release magnet 50 to battery and also through the off normal springs 62' closed upon the first vertical 50 step of the switching mechanism C' , through the winding of the release magnet 50' to battery. Relays 46, 46' and 71 deenergize 55 and restore their armatures to normal. As a result of the restoration of relay 71, the circuits of the relays 12 and 85 are opened, causing their deenergization. Release magnets 50 and 50' energize, release magnet 50 60 operating to release the wipers of the switch-

ing mechanism C, and magnet 50' operating to release the wipers of the switching mechanism C' . The connecting link $C-C'$ is then restored to normal.

By the restoration of the relay 85, the toll 70 trunk conductors 101 and 102 are again connected to the toll trunk conductors 103 and 104, respectively. The toll operator, after removing the plug P' from the jack J' may give the distant toll operator the usual disconnect signal by throwing the key K to the ringing position, thereby extending ringing current from the generator G by way of springs 17 and 17', tip and ring of plug P , tip and ring of jack J , conductors 104 and 103, resting contact and armatures 87 and 86, over trunk conductors 102 and 101 to the distant toll operator's position. After giving the toll operator the disconnect signal, the toll operator at the main toll board removes 85 the plug P from the jack J . Thus all apparatus is again restored to normal.

From the foregoing descriptions, it is evident that a simple and efficient method 90 has been devised whereby an incoming toll call over a toll trunk passing through the exchange which serves the subscriber with which connection is desired, may be set up by the main toll operator at the main toll board in the regular manner through her 95 position by means of an ordinary toll cord; whereby the toll operator, after setting up the connection in the regular way, may cause the talking connection to be extended directly to the subscriber through automatic switches in the exchange serving the called subscriber and in which the distant toll trunk terminates; and whereby the toll operator may have supervision of this toll 100 connection over the toll service line originally used to complete the toll connection.

The invention, its features and the operation of the various mechanisms involved having been described, what is considered new and is desired to have protected by Letters Patent will be specifically stated in the 110 following appended claims.

What is claimed is:

1. In a trunking system, a first and a second line, each line terminating in a jack, a cord circuit for interconnecting said lines through the medium of their associated jacks, a link circuit having a set of movable terminals at each end, fixed terminals for said first line normally disconnected therefrom, fixed terminals permanently connected to the conductors of said second line, an automatic switch for advancing one set of said movable terminals into engagement with the fixed terminals of said second line, a second automatic switch for advancing the other set of said movable terminals into engagement with the fixed terminals of the said first line, means for controlling said automatic switches, means for connecting 115

said normally disconnected fixed terminals to the conductors of said first line, and means controlled over said second line for maintaining said switches operated independent of said controlling means.

5 2. In a telephone system, a first and a second line, a cord circuit, means for connecting said lines through said cord circuit, a link circuit having terminals at each end, 10 an automatic switching mechanism, means for operating said mechanism to connect one end of said link circuit to said second line and the other end of said link circuit to said first line, and means for maintaining 15 said mechanism operated over said second line independent of said operating means.

3. In a telephone system, an operator's position, an operator's cord, an automatic exchange, a first trunk line at said exchange, 20 a second trunk line extending from said exchange to said operator's position, a third trunk line extending from said operator's position to said exchange, an automatic switch at said exchange, a called subscriber's line, 25 operator controlled means for establishing a connection from said first trunk line to said called subscriber via said second trunk line, said cord circuit, said third trunk line, and said automatic switch, a link circuit at 30 said exchange, and operator controlled means for connecting said first trunk line to said automatic switch directly via said link circuit independent of said second trunk line, said cord circuit, and said third trunk 35 line.

4. In a telephone system, an operator's position, an operator's cord, an automatic exchange, a first trunk line at said exchange, a second trunk line extending from said exchange to said operator's position, a third trunk line extending from said operator's position to said exchange, an automatic switch at said exchange, a called subscriber's line, operator controlled means for establishing a connection from said first trunk line to said called subscriber via said second trunk line, said cord circuit, said third trunk line, and said automatic switch, a link circuit at said exchange, and operator controlled means for connecting said first trunk line to said automatic switch directly via said link circuit independent of said second trunk line, said cord circuit, and said third trunk line, said operator controlled means 50 being thereafter controlled solely over said third trunk line.

5. In a telephone system, an operator's position, an operator's cord, an automatic exchange, a first trunk line at said exchange, 60 a second trunk line extending from said exchange, to said operator's position, a third trunk line extending from said operator's position to said exchange, an automatic switch at said exchange, a called subscriber's line, operator controlled means for establishing

ing a connection from said first trunk line to said called subscriber via second trunk line, said cord circuit, said third trunk line, and said automatic switch, a link circuit at said exchange, and operator controlled 70 means for connecting said first trunk line to said automatic switch directly via said link circuit independent of said second trunk line, said cord circuit, and said third trunk line, and means in said cord circuit for maintaining supervision of said connection over said third trunk line.

6. In a telephone system, an operator's position, an operator's cord, an automatic exchange, a first trunk line at said exchange, 80 a second trunk line extending from said exchange, to said operator's position, a third trunk line extending from said operator's position to said exchange, an automatic switch at said exchange, a called subscriber's line, operator controlled means for establishing a connection from said first trunk line to said called subscriber via said second trunk line, said cord circuit, said third trunk line, and said automatic switch, 85 a link circuit at said exchange, and operator controlled means for connecting said first trunk line to said automatic switch directly via said link circuit independent of said second trunk line, said cord circuit, and said third trunk line, means in said cord circuit for maintaining supervision of said connection over said third trunk line, and means associated with said third trunk line 90 for preventing the shunting of voice currents over said third trunk line.

7. In a telephone system, an operator's position, a group of trunks terminating at said position, a second group of trunks accessible at said position, each trunk of said second group terminating in an automatic switch, a called subscriber's line, a cord circuit, means for establishing a connection over any trunk of said first group through said cord circuit over any trunk of said second group and the terminating switch to said subscriber, a plurality of connecting links, an automatic switching mechanism for each of said links, a selecting switch having access to all of said links always 105 connected to an idle one of said switching mechanisms, providing there is one idle, operator controlled means for operating the switching mechanism connected to said selecting switch to connect any one of said first group of trunks to any one of said second group of trunks via the associated link circuit, and means in the operated switching mechanism for automatically causing said selecting switch to hunt a second idle switching mechanism immediately 110 thereafter, said first switching mechanism being thereafter controlled over said any one of said second group of trunks.

8. In a telephone system, a trunk line 120

- terminating in a selecting switch, a plurality of automatic switches accessible to said selecting switch, said selecting switch always being in connection with an idle one 5 of said automatic switches, providing there is one idle, a second trunk line, means controlled over said first trunk line for operating the connected automatic switch to connect with said second trunk line, and means 10 in said automatic switch automatically responsive to the connection of said automatic switch with said second trunk line for causing said selecting switch to connect with a second idle automatic switch.
- 15 9. In a telephone system, a temporarily established connection including a line switch and a second switch, a release trunk conductor, means associated with the second switch for placing a potential on said conductor to maintain said line switch operated, means associated with said second switch for momentarily removing said potential to cause the line switch to release, and means for maintaining the second 20 switch operated.
10. In a telephone system, a temporarily established connection including a line switch and a second switch, a release trunk conductor, means associated with the second switch for placing a potential on said conductor to maintain said line switch operated, means associated with said second switch for removing said potential to cause said line switch to release, means for maintaining said second switch operated, and means for re-applying said potential to guard said second switch against re-seizure by said line switch when said line switch is re-operated. 30
11. In a telephone system, a temporarily established connection including a line switch and a second switch, a release trunk conductor, means associated with the second switch for placing a potential on said conductor to maintain said line switch operated, means associated with said second switch for removing said potential to cause said line switch to release temporarily, although its control circuit is still closed, means for maintaining said second switch operated, and means in said second switch for re-applying a potential to said conductor before the said line switch has had time to re-operate, so that when the re-operation takes place the line switch will hunt for and 40 seize a different switch.
12. In a telephone system, a plurality of automatic switches, a line switch having access thereto, means for operating said line switch to select and connect with an idle one of said automatic switches, means for operating said automatic switch, means for maintaining said automatic switch operated, and means automatically responsive to the completion of the operation of said automatic switch for causing said line switch 45
- to select a second idle automatic switch before said first automatic switch is released. 13. In a telephone system, a first trunk line, a second trunk line, a cord circuit, a third trunk line, a fourth trunk line, means for extending a connection over said trunk lines and said cord circuit in series, means for by-passing said cord circuit and said second and said third trunk lines and for disconnecting said second trunk line, and means for maintaining supervision of said connection over said third trunk line. 70
14. In a telephone system, a first trunk line, a second trunk line, a third trunk line, a fourth trunk line, means for extending a connection over said trunk lines in series, means for by-passing said second and said third trunk lines and for disconnecting said second trunk line, means for maintaining supervision of said connection over said third trunk line, and means associated with said third trunk line for preventing voice current from being shunted over said third trunk line. 75
15. In a telephone system, a first trunk, a second trunk, a third trunk, a fourth trunk, means for extending a connection over said trunks in series, means for by-passing said second and said third trunks by disconnecting said first trunk from said second trunk and connecting it to said fourth trunk, and means for maintaining supervision of said connection over said third trunk. 80
16. In a telephone system, a first group of lines, a branch for each line of said group, a second group of lines, a branch for each line of said second group, means for extending a connection from any line of said first group to any line of said second group via their respective branches, means for bypassing the branches of said lines, and means for maintaining supervision of the connection over the branch of the line of the second group. 85
17. In a telephone system, a first and a second line, means for connecting said lines, a link circuit having terminals at each end, automatic switching mechanism, means for operating said mechanism to connect one end of said link circuit to said second line and the other end of said link circuit to said first line, and means for maintaining said mechanism operated over said second line independent of said operating means. 90
18. In a telephone system, a first and a second line, a link circuit having terminals at each end, automatic switching mechanism, operator-controlled means for operating said mechanism to connect one end of said link circuit to said second line and the other end of said link circuit to said first line, and means for maintaining said mechanism operated over said second line independent of said operating means. 120
19. In a telephone system, a first line, a 130

- second line, a subscriber's line, an automatic switch terminating said second line, a cord circuit, operator-controlled means for establishing a connection from said first line to said subscriber's line via said cord circuit, said second line, and said automatic switch, a link circuit, and operator-controlled means for connecting said first line to said automatic switch directly via said link circuit independent of said cord circuit and said second line. 5
20. In a telephone system, a first and a second line, a subscriber's line, an automatic switch terminating said second line, operator-controlled means for establishing a connection from said first line to said subscriber's line via said second line and said automatic switch, a link circuit, and operator-controlled means for connecting said first line to said switch directly via said link circuit independent of said second line. 10
21. In a telephone system, a first and a second line, a subscriber's line, an automatic switch terminating said second line, operator-controlled means for establishing a connection from said first line to said subscriber's line via said second line and said automatic switch, a link circuit, and operator-controlled means for connecting said first line to said switch directly via said link circuit independent of said second line. 15
25. In a telephone system, a first and a second line, a subscriber's line, an automatic switch terminating said second line, operator-controlled means for establishing a connection from said first line to said subscriber's line via said second line and said automatic switch, a link circuit, operator-controlled means for connecting said first line to said switch directly via said link circuit independent of said second line, and means for maintaining the latter connection intact independent of the latter operator-controlled means. 20
30. 22. In a telephone system, a first and a second line, a subscriber's line, an automatic switch terminating said second line, operator-controlled means for establishing a connection from said first line to said subscriber's line via said second line and said automatic switch, a link circuit, operator-controlled means for connecting said first line to said switch directly via said link circuit independent of said second line, and means for maintaining the latter connection intact over said second line. 25
35. 23. In a telephone system, an automatic exchange, a toll board, a trunk line passing through said exchange and extending to said toll board, operator-controlled means for establishing a connection from said trunk line to a subscriber's station at the automatic exchange, and auxiliary apparatus at the automatic exchange for establishing a connection from said trunk line to said subscriber's station exclusive of the section of the trunk line extending from the automatic exchange to the toll board. 30
40. 24. In a telephone system, an automatic exchange, a toll board, a toll line passing through said exchange and extending to said toll board, a service trunk extending from said toll board to said automatic exchange, means including said service trunk for establishing a connection from said toll line to a subscriber's station at said automatic exchange, an auxiliary apparatus at the automatic exchange for establishing a connection from said toll line to said subscriber's station exclusive of the section of the toll line between the automatic exchange and the toll board and also exclusive of said service trunk. 45
50. 25. In a telephone system, an automatic exchange, a toll board, a group of toll lines passing through said exchange and extending to said toll board, a group of service trunks extending from said toll board to said automatic exchange, means for extending connections from the toll lines via the service trunks to subscribers' stations at the automatic exchange, a plurality of switching mechanisms at the automatic exchange, and a common control circuit for operating said switching mechanisms separately to by-pass the sections of the toll lines between the automatic exchange and the toll board and also the service trunks included in such connections. 55
55. 26. In a telephone system, an automatic exchange, a toll board, a group of toll lines passing through said exchange and extending to said toll board, a group of service trunks extending from said toll board to said automatic exchange, means for extending connections from the toll lines via the service trunks to subscribers' stations at the automatic exchange, a plurality of switching mechanisms at the automatic exchange, and means for maintaining each switching mechanism operated independent of the common control circuit over the service trunk by-passed thereby. 60
60. 27. In a telephone system, a first and a second line, a plurality of link circuits having terminals at each end, a selecting switch for selecting an idle one of said link circuits, operator-controlled means for connecting the terminals of one end of the selected link circuit to said first line and the terminals of the other end of the selected link circuit to said second line to connect said lines, and means for causing said selecting switch to select the next idle link circuit at the completion of said connection. 65
65. 28. In a telephone system, a first and a second line, a plurality of switching mechanisms, a selecting switch for selecting an idle switching mechanism, a third line terminating in said selecting switch, means controlled over said third line for operating the selected switching mechanism to connect said first and said second line, and means responsive to the completion of said connection for causing said selecting switch to select another idle switching mechanism. 70
70. 29. In a telephone system, a first and a second line, a plurality of switching mechanisms, a selecting switch for selecting an idle switching mechanism, a third line termi- 75

nating in said selecting switch, and means controlled over said third line for operating the selected switching mechanism to connect said first and said second line to extend a call, means for then causing said selecting switch to select another idle switching mechanism, and means for maintaining the oper-

ated switching mechanism in position until the termination of the call.

In witness whereof, I hereunto subscribe ¹⁰ my name this 20th day of February A. D., 1926.

BERNARD D. WILLIS.
